DEVICE FOR PREVENTING OVERTRAVEL OF
OPERATING MECHANISMS

Alan C. Davis, East Haddam, Conn.

Application March 9, 1945, Serial No. 581,864.

2 Claims. (Cl. 137—156.5)

1

The present invention relates to a device to be used in conjunction with a temperature or pressure responsive instrument such as a switch or valve to eliminate excessive movement of parts thereof which might result in damage to the instrument.

Specifically, the device includes a single manually operated nut carried by the operating part of the control instrument to calibrate the part; overtravel limitations is also accomplished by the nut, preventing damage to the instrument parts; and excessive movement of instrument parts caused by pressure pulsations in the fluid system is prevented by the nut and its associated structure.

Another object of the invention is to provide a device of this character which may be readily adapted for use on mechanisms where the use of control devices is desired.

Other objects of the invention will be apparent from the following description of the present preferred form of the invention, taken in connection with the accompanying drawings, wherein:

Figure 1 is a side elevation of a device constructed in accordance with the present invention illustrating its application, parts thereof being shown in section to disclose details; and

Figure 2 is a perspective view of the calibrating nut of the present invention.

In order to illustrate the application of my invention, I have in Figure 1 shown diagrammatically an internal combustion engine 3 and a pump 4, the engine and pump being in communication with a pressure lubricating line 5, the latter having tapped thereinto a branch line 6. The branch line 6 in turn communicates with a spring loaded flexible bellows, generally designated 7, which may be of standard construction. The spring of the bellows, indicated at 8, is convoluted about a sleeve or bushing 9, which latter is carried by a casing wall 10 of the pressure responsive device. One end of the spring 8 engages said wall while the opposite end engages a disc 11 secured to one end of the bellows 7, the disc being equipped with a shaft 12. The shaft 12 extends through the bushing 9 and wall 10, its outer end being screw-threaded as indicated at 13. The inner face of the wall 10 carries a frame generally designated 14, the inner terminal of which carries an abutment or barrier 15. In some cases the wall 10 may act as the lower barrier. The frame also includes an abutment or barrier 16 which extends in parallel relation to the intermediate part of the abutment 15 and the wall 10, the abutment 16 being provided with

2

an opening 17 through which the shaft 12 extends. The abutment 16 is also provided with an opening indicated at 18 which is in alignment with the opening 17, and the axis of bushing 9.

5 The threaded end of the shaft 12 is adapted for engagement by a complementally threaded nut 19 one end of the latter being of larger diameter than the diameter of the opening indicated at 18. The opposite end 20 of the nut is of considerably smaller diameter and is engaged through said opening 18.

As set out above, and shown to advantage in Figure 2, the end of the nut of larger diameter is provided with a screw-threaded recess with which 15 a setscrew 21 communicates, in order that the nut may be held in a fixed position on the shaft 12 when desired. The extreme outer terminal of the smaller diameter end 20 of the nut is closed, for a purpose hereinafter set forth.

20 Also mounted on the frame 14 is a switch mechanism generally designated 22, a moving part 23 of which engages the closed outer terminal of the smaller diameter end 20 of the nut. Movement of the nut through the abutment 16 effects movement of the element 23 for a purpose which will be presently described.

25 Reduction or increase in the pressure of the lubricating oil passing through the line 5, to a predetermined value, results in a corresponding reduction or increase in pressure in the bellows, permitting the latter to be collapsed under the expansive force of the spring 8 if the pressure decreases, or to expand against the thrust of said spring if the pressure increases. Correspondingly, the shaft 12, carried by the bellows, moves toward the oil pressure line 5 if the pressure decreases, or away from said line if the pressure increases, automatically effecting operation of the moving part 23 of the switch 22, resulting in 30 the performance of some predetermined function designed to give warning of an undesirable condition or to prevent damage to the engine. This function may be to give a visual and/or auricular signal or may set in motion other mechanism to 35 accomplish the objects of the invention.

40 I have found after much experiment, that by use of the present means a greatly simplified device is provided which is more accurate and positive in its operation. This is due principally to the nut 19 and its associated mechanism. The peculiar yet simple structure here employed, results in three distinct functions resulting in ease of calibration and positive operation; prevention of damage to the instrument due to over extension of the flexible bellows; and long instru- 45

ment life due to elimination of bellows movement under pulsating pressures in the fluid system to which the instrument is connected, as follows:

1. Calibration is accomplished by manually adjusting the nut 19 on the shaft 12 and securing it, if desired, at the predetermined point of adjustment, by means of set screw 21.

2. Overtravel of the moving parts of the assembly which would cause damage to the switch, and distortion of the bellows or diaphragm, which would cause change in instrument calibration or bellows or diaphragm failure is prevented, since the extent of movement of the shaft 12 is limited by the abutments 15 and 16; and

3. Rapid flexing of the bellows or diaphragm which would be caused by pulsating pressures in the fluid system at pressures above or below the calibrated setting of the instrument is also prevented, by reason of the limited travel allowed the nut 19 between the abutments 15 and 16. Rapid flexing of the bellows or diaphragm due to pulsating pressures in the fluid system not otherwise prevented, would result in very early failure of the bellows or diaphragm, due to fatigue of bellows or diaphragm material.

While I have herein described a preferred form of the invention, it is nevertheless to be understood that various changes may be made within the scope of the claims hereto appended.

What I claim is:

1. In a pressure or temperature responsive device, parallel abutments, a threaded shaft and a nut, the threaded shaft extending through one

of the abutments and engaged with the nut, an end of the nut being extended and engaged through the other abutment, and mechanism engageable upon movement of the latter.

2. In a pressure or temperature responsive device, a frame equipped with fixed abutments, a spring operated shaft extending through one of said abutments, a nut threaded on the shaft, one end of the nut extending through the other abutment, the nut being adjustable on the shaft to adjust its extent of travel between the abutments, the extended terminal of the nut being adapted for engagement with a part to be moved.
